SHEET TRANSFER AND GUIDE

Robert J. Kovatch, Baltimore, Md., assignor to
Bethlehem Steel Company, a corporation of
Pennsylvania

Application July 16, 1949, Serial No. 105,325

4 Claims. (Cl. 198—27)

1

My invention relates generally to a sheet feeding device and is more particularly adapted for use in the manufacture of tin plate, although it can be used for feeding sheets of other material equally as well where a similar purpose is desired.

In the manufacture of tin plate after it is rolled and cut into sheet sizes usually 20" x 28" they are passed through an electric cathodic cleaner. The uncoated sheets are then advanced therefrom by a pair of over-shot conveyors which drop the sheets onto a table which feed them in two rows into a tin pot and then to a catcher for receiving the coated plate as it comes from the tin pot, a cooling and washing table, a branner or polishing machine, and finally to a piler.

My feeding device which I will designate as a sheet balancer and guide is illustrated for use in two positions. In the first case it is shown used in conjunction with an over-shot conveyor table which receives the sheets after they leave the electric cathodic cleaner, and in the second case it is used attached to the tin plate piler box.

When used in conjunction with the over-shot conveyor which receives the sheets from the electric cathodic cleaner the sheet balancer and guide is attached to the over-shot conveyor and handles wet, uncoated material. The sheets of wet, uncoated plates drop from the over-shot conveyor onto the sheet balancer which in turn drops the sheets onto the table for feeding it into the tin pot. Since the over-shot conveyor feeds sheets in two distinct rows or positions onto the table, a sheet balancer is needed for each of the sheet positions of the table. These two balancers operate in exactly the same manner.

The sheet balancer and guide is used to drop the sheets onto the table straight and flat so that one edge cannot hit first causing bending, scratching and cobbling of the sheets feeding into the tin pot. In this position the balancer also keeps the wet sheets from sticking together before they are straight and aligned. A screw adjustable weight on each sheet balancer can be adjusted to make the balancer trip at the right time for any weight of sheet.

Before the installation of the sheet balancer and guide, scratches of the previous sheet were prevalent due to the rough shear edge dragging as the sheet fell, light gauge sheets and sheets with de-wet spots had a tendency to stick to the previous sheet. This condition caused kinks, broken product, cobbles and loss of production, due to stoppage of the unit. It was necessary to keep a man on duty the entire turn to watch for these conditions. Since the installation and

2

operation of the sheet balancer and guide, these hazards and extra cost have been eliminated.

When the sheet balancer and guide are used in conjunction with a tin plate piler, a sheet balancer and guide is attached to each side of the top of the piler box and handles dry tin plate. The sheets of tin plate after they come out of the branner cleaner are fed by a conveyor to an inclined trough down which they slide by gravity onto the sheet balancers which drop the sheets into the sheet piler. The sheet balancer drops the sheets flat and straight in the piler, so that one edge will not drop on the pile first, avoiding kinks, cobbles, bending and scratching surfaces in the pile. Here also an adjustable weight is provided for each balancer so that any weight of sheet can be dropped onto the pile at the correct time.

One of the objects of my invention is to provide a sheet balancer and guide adapted to receive sheets as they leave a conveyor or the like and guide the same to its proper position over an automatic feeding table or the pile in a sheet piler and drop the sheets in such a manner so that it eliminates operational difficulties.

Another object of my invention is to provide a sheet balancer and guide that will receive a sheet as it leaves a conveyor or the like and guide the sheet to its proper position over an automatic feeding table or the pile of sheets in a sheet piler and drop the sheet in such a manner so as to prevent scratching of the previously fed sheet due to the rough shear edge dragging as the sheet fell, and to prevent the tendency of the sheets from sticking to the previous fed sheet on the automatic feeding table, thereby preventing kinks, broken product, cobbles and loss of production, due to the stoppage of the unit.

A further object of my invention relates to the screw adjustable weight on each sheet balancer that can be adjusted to make the balancer trip at the right time for any weight of sheet.

Other objects and advantages of my invention will hereinafter appear.

Referring now to the accompanying four sheets of drawings which form a part of this specification and on which like characters of reference indicate like parts:

Figure 1 is a perspective view of the over-shot conveyor showing two sheets from the electric cathodic cleaner being delivered to the automatic feeding table for feeding the sheets into the entry side of the tin pot and showing a pair of sheet balancers and guides attached thereto.

Fig. 2 is a top plan view of the sheet balancer

with the guide plate removed to more clearly show its construction.

Fig. 3 is an end elevation of the sheet balancer and guide as viewed from the left hand end of Fig. 2.

Fig. 4 is a detail section view of one of the pivotal bearings for the sheet balancer and guide.

Fig. 5 is a front elevation of the sheet balancer and guide.

Fig. 6 is an end elevation of the sheet balancer and guide as viewed from the right hand end of Fig. 2.

Fig. 7 illustrates the operation of the sheet balancer and guide for depositing a sheet on the automatic feeding table from which it is fed into the tin pot.

Fig. 8 illustrates the operation of the pair of sheet balancers and guides for depositing a sheet on the pile of sheets in the tin plate piler, and

Fig. 9 is a perspective view showing the manner of feeding the sheet to the tin plate piler, with the sheet balancers shown in a slightly modified form.

Referring now to the various characters of reference on the drawings, and first to Figs. 1 to 7 inclusive, the numerals 1 and 2 indicate the upper and lower over-shot conveyors respectively, which receive the wet sheets from the electric cathodic cleaner, (not shown) and feed them to the automatic feeding table 3, which is provided with vertical transversely extending guard plates 4, 5, 6 and 7, which divide the table into two lines of feed 8 and 9 for the sheets and advance them into the tin pot. The guard plates 5 and 7 acting as stops for limiting the forward movement of the sheets 10 and 11.

A sheet balancer and guide is mounted above each of the outer ends of each line of feed 8 and 9 for the sheets, comprising a main frame 12 having an extending arm 13 at one end and a similar arm 14 at an intermediate point in which the sheet balancer 15 is pivoted. The main frame 12 is provided with a hanger bracket 16 at one end, the upper end of which is bent as at 17 to embrace a transversely extending angular member 18 of the over-shot conveyor and secured thereto by means of a set bolt 19 threaded into a boss 20 and provided with a handle 21 for manipulating the set bolt for clamping the end of the hanger bracket 16 to angle 18.

A guide plate 22 connects the outer ends of the arms 13 and 14 and is attached thereto by means of screws 23.

The sheet balancer 15 is of substantially rectangular outline in top plan and is formed of rod members, the inner rod 24 having a greater cross sectional area than the rod which forms the ends 25 and the outer rod 26, these being formed in one piece and the ends of 25 welded as at 27 to the inner rod 24. The ends 25 each have axle extensions 28 journaled in bearings 29 in the arms 13 and 14 of the main frame 12 each provided with a cover 30 attached to each of said arms 13 and 14 by means of a screw 31. The outer ends of 25 are arc shaped as at 32 to extend under the guide plate 22.

A U-shaped rod 33 has the end of one of its legs 34 which is shorter than the other leg welded as at 35 to one end of the inner rod 24, while the other leg 36 is somewhat longer than the other and extends adjacent to the arm 13 of the main frame 12 and is screw threaded as at 37 to receive an adjustable balance weight 38 which

is more securely held in position by means of a nut 39. Normally the weight 38 holds the ends 25 and the outer rod member 26 in the raised position with the leg 34 of the U-shaped rod 33 engaging the top surface of the main frame 12.

As illustrated more clearly in Figs. 1 and 7 the sheet as it is fed forward by the over-shot conveyor to the automatic feeding table 3 has one edge of the sheet supported by the stationary rod 40 which may be adjusted for different widths of sheets while the other edge of the sheet is initially supported by the outer rod member 26 of the sheet balancer 15. As the sheet continues to advance, the balance weight 38 being properly adjusted, the weight of the sheet will depress the rod 26 of the balancer and the sheet will slide off the stationary rod 40 and be deposited on the automatic feeding table 3 in position indicated in Fig. 7 where the rollers will advance the sheet between the pairs of rollers 41 to feed the sheet into the tin pot 42 located adjacent thereto. After the coated sheet passes through the tin pot, a cooling and washing table, and a branner or polishing machine, it is conveyed to a piler to collect them in piles or stacks from which they are loaded on trucks and taken to the assorting room where they are placed upon well lighted tables for inspection, all of which is well known in this art.

Referring now to Figs. 8 and 9 which illustrates the piling operation.

When used in conjunction with the tin plate piler, a sheet balancer is attached to opposite sides of the top of the piling box 43. The sheets as indicated at 44 in Fig. 9, after they come out of the branner or polishing machine and are then fed by means of rollers 45 to an inclined trough 46 down which they slide by gravity onto the sheet balancers 15.

As indicated in Fig. 9 two spaced piling boxes 43 are shown of similar construction which are connected together by means of a plate structure as at 47. The trough 46 has a supporting base 48 which is pivoted to 47 as at 49. The supporting base 48 has an arc shaped arm 50 attached thereto and is provided with a set bolt 51, which extends through an arc shaped slot 52 in the plate 47 and provided with an adjustable hand wheel nut 53. As illustrated in Fig. 9, the sheet 44 is being discharged into the front piling box 43 to form a pile or stack 54. After the stack has been built up to the desired height 55 the hand wheel nut 53 is unscrewed slightly and the back end of the trough is tilted downwardly manually to allow the sheets to be discharged into the rear piling box, the hand wheel nut 53 is then tightened to clamp the trough 46 in this position. In this manner while the stack in the forward piling box is being removed the stack in the rear piling box is being formed, in this manner the trough is readjusted after each stack is formed and the operation is continuous.

The piling boxes each have a base 55 and side plates 56 and 57, the latter of which is preferably hinged. The upper portions of the side plates are inclined outwardly as at 58 to form guides for the sheets and are provided with journal bearings 59 for the axles 60 of the sheet balancers which extend inwardly from the rod members of the end rod members 25 and these outwardly inclined portions 58 are each provided with a stop 61 to limit the outward movement 75 of the rod member 24.

Each piling box is provided with a swinging door 62 at the outer end having buffer plates 63 on the inner side for limiting the forward movement of the sheets when they are discharged into the piling box. Each door 62 is supported by a standard 64 in which is mounted a swinging arm 65 the outer end having a threaded bolt 66 mounted therein and adapted for adjustment by means of a hand wheel nut 67 and a lock nut 68. The lower end of the threaded bolt 66 is provided with a cross bar 69 with its end portions connected by means of chains 70 to the door 62.

The operation of the sheet balancer for the sheet piler is substantially the same as for automatic feeding table 3 and where the structure of the sheet balancer is the same, the same reference numerals will apply thereto. The sheet as it is fed by gravity from the inclined trough 43 engages the outer rod members 26 of the two sheet balancers 15 and the weight of the sheet will tilt the balancers, and the sheet will be discharged into the piler box as indicated in dotted lines in Fig. 3.

In Fig. 9 I have shown a slight modification in which one end of each of the threaded rods for the weights 33 is welded as at 71 to the rod member 24 of the sheet balancer and in Fig. 8 I have illustrated the threaded rod 72 for the adjustable weight 33 as substantially L-shaped, but the operation of the balancers shown in Figs. 8 and 9 is substantially the same as that described for Figs. 1 to 7 inclusive. After each stack 54 is completed the door 62 is swung out of position and a truck having a lower shelf like projection is adapted to extend under the stack and convey it to the room for inspection.

Although I have shown and described my invention in considerable detail, I do not wish to be limited to the exact construction shown and described, but may use such substitutions, modifications or equivalents thereof, as are embraced within the scope of my invention, or as pointed out in the claims.

I claim:

1. Apparatus for delivering lengths of sheets to a feeding table, a conveyor for delivering sheets in sequence to the feeding table to advance the sheets in a path at right angles to that of the conveyor, a stationary means mounted above the feeding table for supporting one side of the sheet during delivery from the conveyor, a sheet balancer for supporting the other side of the sheet comprising a main frame having a hanger bracket attached to the frame of the conveyor mounted above the feeding table, spaced arms extending from the main frame, a journal box formed in each spaced arm, said sheet balancer having an inner horizontally extending rod member and an outer horizontally extending rod member, end rods connecting the ends of the inner and outer rod member, an axle extending from each of the end rod members journaled in the boxes of the spaced arms, said outer horizontally extending rod member engaging and initially supporting the other side of the sheet and adapted to yield under the weight of the side of the sheet and disengage the other side of the sheet from the stationary support and drop the sheet on the feeding table.

2. Apparatus for delivering lengths of sheet to a feeding table, a conveyor for delivering sheets in sequence to the feeding table, a pair of spaced vertical transversely extending guard plates mounted on the feeding table, a rod connecting

the pair of guard plates for supporting one side of the sheet during delivery from the conveyor, a sheet balancer for supporting the other side of the sheet, comprising a main frame having a hanger bracket attached to the frame of the conveyor and mounted above the feeding table, a pair of spaced arms extending from one side of the main frame, a journal box formed in each spaced arm, said sheet balancer having an inner 5 horizontally extending rod member and an outer horizontally extending rod member of smaller cross sectional area than the inner member, end rods connecting the ends of the inner and outer horizontally extending rod members, an axle extending from each of the end rod members journaled in the boxes of the spaced arms, said outer horizontally extending rod member normally engaging and initially supporting the other side of the sheet and adapted to yield under the weight of the side of the sheet and disengage the other side of the sheet from the rod support and drop the sheet on the feeding table, automatic means for returning the sheet balancer to its normal position, and means for limiting the movement of the sheet balancer.

3. Apparatus for feeding lengths of sheets from an electric cathodic cleaner to a tin pot, a conveyor for delivering sheets from the electric cathodic cleaner in sequence to a feeding table, a pair of spaced vertical transversely extending guard plates mounted on the feeding table, a rod connecting the pair of guard plates for supporting one side of the sheet during delivery from the conveyor, a sheet balancer mounted above the feeding table for supporting the other side of the sheet, comprising a main frame having a hanger bracket attached to the frame of the conveyor, a pair of spaced arms extending from one side of the main frame, a journal box formed in the end portion of each spaced arm, said sheet balancer having an inner horizontally extending rod member and an outer horizontally extending rod member, end rods connecting the ends of the inner and outer horizontally extending rod members, an axle extending from each of the end rod members journaled in the journal boxes of the spaced arms, said outer horizontally extending rod member adapted to normally engage and initially support the other side of the sheet and adapted to yield under the weight of the side of the sheet and disengage the other side of the sheet from the rod support and drop the sheet on the feeding table to advance the sheet into the tin pot, a U-shaped rod having one leg secured to the inner horizontally extending rod member and the other leg threaded to receive a weight threaded for adjustment on the threaded leg portion of the U-shaped rod to allow sheets of different weights to drop onto the feeding table at the desired time and to return the sheet balancer to its normal position after the sheet is dropped.

4. Apparatus for feeding lengths of sheets from an electric cathodic cleaner to a tin pot, a conveyor for delivering lengths of sheets received from the electric cathodic cleaner to a feeding table in sequence, a pair of spaced vertically transversely extending guard plates mounted above the feeding table, a stationary rod connecting the guard plates for supporting one side 65 edge of each sheet during delivery from the conveyor, a sheet balancer for normally supporting the other side of the sheet, comprising a main frame having a hanger bracket attached to the frame of the conveyor mounted above the feeding table adjacent to the stationary rod support, a

pair of spaced arms extending from one side of the main frame, a journal box formed in each spaced arm, a vertically extending inclined guide plate connecting and secured to the ends of the pair of spaced arms, said sheet balancer having an inner horizontally extending rod member and an outer horizontally extending rod member, end rods connecting the ends of the inner and outer rod members each having an arc shaped outer portion adapted to extend under the lower edge 10 of the guide plate, an axle extending from each of the end rod members journaled in the journal boxes of the spaced arms, said outer horizontally extending rod member engaging and initially supporting the other side of the sheet and adapted to yield under the weight of the side 15 of the sheet and disengage the other side of the sheet from the stationary rod to allow the sheet to drop on the feeding table to advance the sheet into the tin pot, a threaded rod secured at one 20 end to the inner horizontally extending rod mem-

ber adapted to receive a weight threaded thereon for adjustment on the threaded rod to allow sheets of different weights to drop onto the feeding table at the desired time and to return the sheet balancer to its normal position after the sheet has been dropped onto the feeding table.

ROBERT J. KOVATCH.
